Attorney.

UNITED STATES' PATENT OFFICE.

THOMAS P. GLENDY AND OSCAR V. GLENDY, OF INDIANAPOLIS, INDIANA.

FRONT STORM-WINDOW FOR LOCOMOTIVE-CABS.

1,360,393.

Specification of Letters Patent. Patented Nov. 30, 1920.

Application filed April 26, 1920. Serial No. 376,772.

To all whom it may concern:

Be it known that we, THOMAS P. GLENDY and OSCAR V. GLENDY, citizens of the United States, residing at Indianapolis, in the county of Marion and State of Indiana, have invented new and useful Improvements in Front Storm-Windows for Locomotive-Cabs, of which the following is a specification.

This invention relates to means for retaining glass lights in storm windows for locomotive engine cabs. Heretofore these have commonly been held in their iron frames or sashes by plaster of Paris, used instead of putty because of the hardness and difficulty of removing the latter to replace broken lights. The lights are broken frequently and under the rules followed by locomotive engineers the latter will refuse to take out an engine with a broken storm glass but will hold the engine idle until the broken light has been replaced with a whole one. The resulting delay frequently causes disarrangement of the train schedules and much loss and damage to the railroad.

The object of our invention is to retain the glass in its frame or sash by a spring means which will afford quick and easy removal of broken lights and the insertion of new ones, and which will hold the glass panes securely in place and prevent rattling.

We accomplish the above and other objects which will hereinafter appear, by the mechanism illustrated in the accompanying drawing, in which—

Figure 1, is a perspective view of a cab window with a storm light partly open. The light is secured by a spring means in accordance with the teachings of our invention. Fig. 2 is a perspective view illustrating the manner of insertion of a new light. Fig. 3 is a vertical section of a frame with the light in place and held by our improved means and Fig. 4 is an edge view of one of the springs removed from the other parts.

The storm windows of locomotive engines are located in a door which affords egress from the cab to a running-board at the side of the engine; consequently it is more than ordinarily subject to injury by the passing of the engineer in and out through the narrow opening, and to slamming of the door, and it is also important that the glass be kept whole because the view of the track ahead is through it and if the glass be broken the rush of air caused by the speed of the

train throws a fusilade of cinders and dirt, or of blinding rain or snow into the engineer's eyes.

In the window-opening of door 5 are generally two glass lights 6 and 7. The light 6 is a fixed one while the light 7 is capable of a swinging outward adjustment to various angles to provide a sight opening below when rain or snow on the glass would obstruct the view.

This light 7 is mounted in an iron frame or sash comprising a top horizontal member 8, and vertical ends 9, 9. There is no horizontal lower frame member because one there would obstruct the view and for that reason it is omitted, and because of such omission the glass is unsupported there and is therefore much more easily broken. The ends 9, 9, are angle bars, and the horizontal bar 8 is channeled, the channel forming a seat for the upper edge of the glass; and, to direct and wedge the edge into place the top flange 10, of the channel is beveled on the side toward the glass, in the manner shown in Fig. 3.

The sash thus filled is hinged at its upper edge in an iron frame 11, in turn fixed to the door 5. The frame 11 has an ear 12 with a pin 13, and the adjustable window sash has a rack-bar 14, the series of notches in which may successively be made to engage pin 13, and hold any given elevation of the swinging sash. This much of the construction is old with the exception of the channel and beveled flange 10, the glass having heretofore been secured in members 8 and 9, 9, by plaster of Paris.

The novel feature of greatest importance in our invention is the use of springs to clamp and retain the glass in the hinged frame. Various forms of spring for this purpose may be used and have been used by us, but the best embodiment so far known to us is that substantially as shown in the drawings which is in duplicate,—one for each end member 9, 9, and which is a leaf spring having a member *a* to lay against the opposite or outer side of the end member from the glass, to which it is fastened by a stove-bolt 15. The member *a* is continued at right angles, with or without rounded corners, to form the member *b*, crossing to the inner side of the sash, and thence in a return direction substantially parallel with member *a* to form the member *c*, which preferably extends past the bolt 15.

15 and is bowed toward the glass to secure extended and positive contact with the latter, in the manner shown in Fig. 3.

To insert a glass pane the springs on both 5 ends of the sash are sufficiently flexed to raise the loose member *c* clear of the frame, and thereupon the ends *b* are swung outwardly around bolts 15, to positions shown 10 in Fig. 2, leaving the way clear for the edgewise introduction of the glass in the manner shown in Fig. 2; and when the glass is placed the springs are both turned back to first position across the edge of the glass 15 with the members *c* pressing against the sides of the glass and holding the latter to the sash.

With our improved means an engineer may carry extra panes of glass with him and can replace a broken light himself in a 20 few seconds, whereas under old conditions it was necessary to send the engine to a shop or bring an expert workman from there to do the job, causing delay in either of the last cases.

25 We do not desire to be limited to the form and application of spring here shown, nor to the construction of the sash which is mainly the same as has been heretofore used and not as well adapted to our means 30 as would obtain if specially designed; but what we do claim as new and wish to set are by Letters Patent of the United States, is—

1. The combination in a locomotive engine cab and a storm-door therefor, of an 35 upper sash swingingly mounted in the door, a glass supported by the sash, and spring

means for retaining the glass in the sash each spring having a portion pressing the glass against the sash and another portion 40 secured to the opposite side of the frame from the glass.

2. The combination in a locomotive engine cab and a storm-door therefor, of a sash open at the bottom and swingingly 45 mounted in the door, a glass supported by the sash, and spring means for retaining the glass in the sash, each comprising portions pressing the glass against the sash and other portions secured to the opposite side of the 50 frame from the glass.

3. In a device for the purposes specified, a sash open at the bottom, a glass supported by the sash, and a leaf spring bent in U-shape having one stem pressing the glass 55 against the sash and the other stem pivotally secured to the opposite side of the frame from the glass.

4. In a device for the purposes specified, a sash having a top horizontal channel bar 60 with an inwardly beveled outer flange, said sash having no lower rail, a glass supported by the sash, and spring means for retaining the glass in the sash.

5. In a device for the purposes specified, 65 a sash having a channeled top rail the channel being inwardly beveled and said sash having angle-bar side rails, a glass in the sash and spring means for retaining the glass.

Signed at Indianapolis, Indiana, this the 24 day of April, 1920.

THOMAS P. GLENDY.
OSCAR V. GLENDY.
